US0D1063590S

(12) **United States Design Patent** (10) **Patent No.:** **US D1,063,590 S**
(45) **Date of Patent:** **** Feb. 25, 2025**

(54) **SMART LOCK**

(71) Applicant: **TONG LUNG METAL INDUSTRY CO., LTD.**, Minxiong Township, Chiayi County (TW)

(72) Inventors: **Mei-Ching Chu**, Chiayi (TW); **Chun-Yi Fang**, Huwei Township, Yunlin County (TW); **Pai-Hsiang Chuang**, New Taipei (TW); **Chen-Ming Lin**, Minsyong Township, Chiayi County (TW); **Yu Lin**, Chiayi (TW); **Ruei-Jie Jeng**, Jhuci Township, Chiayi County (TW); **Ding-Sian Cai**, Singang Township, Chiayi County (TW)

(73) Assignee: **TONG LUNG METAL INDUSTRY CO., LTD.**, Minxiong Township, Chiayi County (TW)

(**) Term: **15 Years**

(21) Appl. No.: **29/865,359**

(22) Filed: **Jul. 21, 2022**

(51) **LOC (15) Cl. 08-07**

(52) **U.S. Cl.**

USPC **D8/331**

(57) **CLAIM**

The ornamental design for a smart lock as shown and described.

DESCRIPTION

FIG. 1 is a perspective view of a smart lock having a first unclaimed configuration on the front panel, showing our new design;

FIG. 2 is a front elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a perspective view thereof in a state of use;

FIG. 8 is a perspective view of a smart lock having a second unclaimed configuration on the front panel;

FIG. 9 is a front elevational view thereof;

FIG. 10 is a left side elevational view thereof;

FIG. 11 is a right side elevational view thereof;

FIG. 12 is a top plan view thereof;

FIG. 13 is a bottom plan view thereof; and,

FIG. 14 is a perspective view thereof in a state of use.

The dashed broken lines depict portions of the smart lock that form no part of the claimed design.

The dot-dash broken lines are for illustrating environment structure only and form no part of the claimed design.

1 Claim, 10 Drawing Sheets
